JAMES CONNOR, THOMAS O. CARTER, AND ALBERT RAY, OF BARSTOW, CALIFORNIA.

RAILROAD-TIE PLATE.

No. 919,133.

Specification of Letters Patent.

Patented April 20, 1909.

Application filed December 12, 1908. Serial No. 467,124.

To all whom it may concern:

Be it known that we, JAMES CONNOR, THOMAS O. CARTER, and ALBERT RAY, citizens of the United States, residing at Barstow, in the county of San Bernardino and State of California, have invented certain new and useful Improvements in Railroad-Tie Plates, of which the following is a specification.

10 This invention relates to means for securing railroad rails to the cross ties of the track, in which a tie plate which forms a seat or bearing for the rail is interposed between the base of the rail and the cross tie and is provided on its under side with tapered ribs which bury into the tie.

15 The object of the invention is to secure a firm connection between the rail and tie which shall be free from all tendency to work loose or rattle, by a simple, cheap and practical construction and to provide for the accommodation of rails of varying cross sections and weights, thus making the tie plate universal in its application.

20 25 The invention consists in the novel construction of the tie plate as will be herein-after more fully described with reference to the drawing, in which—

Figure 1 is a top plan view of the anti-rattle tie plate, Fig. 2 an underneath view of the same, Fig. 3 is a vertical longitudinal section taken on line 3—3 of Fig. 1 and showing the same applied to a railroad tie, and indicating in dotted lines the position of the 30 rail and spikes, and Fig. 4 is a section through the plate, taken on line 4—4 of Fig. 1.

In the drawing A represents the plate, which for standard sizes is about 6 by 10 inches. This plate is made thicker on the 35 outer side, next to the end of the tie, and tapers to an increasing thinness toward the middle of the tie. On its thicker side it is formed with an overhanging lip or flange B of uniform cross section extending the full 40 width of the plate. This lip is designed to lap over one side of the base of the rail and on this thicker side, just outside the lip or flange B, the plate is formed with one or more holes D for one or more spikes. On 45 the other side of the position of the rail the plate is formed with a plurality of sets of spike holes D¹ D¹, D² D² and D³ D³. The holes D¹ D¹ are spaced away from the flange B a distance adapted to coincide with the 50 opposite side of the rail base for the smallest size of rail R, indicated in dotted lines. The

holes D² D² are adapted to take the rail base of the next larger size of rail, and the holes D³ D³ are adapted to take a still larger size of rail base, it being understood that when the 55 spikes are driven through either of these sets of holes the spikes will engage with and overhang and secure these different sizes of rails, such as seventy-five pound rails, eighty-five pound rails, or ninety-five pound rails. 60 These sets of holes may be increased or diminished to correspond to any size or weight of rail. The upper face of the plate which receives the base of the rail is made slightly inclined, dipping toward the center of the 65 tie, for the purpose hereafter described and this portion of the face of the plate is provided with any desired number of parallel grooves a a for the purpose of reducing the weight of the plate. 70

75 On the under side the plate is formed with straight ribs C C¹ C, of uniform cross section. These ribs have sharp edges, as seen in Fig. 4, and the outer ones C C are of a slightly greater vertical depth than the middle one C¹. The outer ribs are arranged at a reverse inclination to each other and are at a greater distance apart at the outer end of the plate bearing lip B or the end next to the end of the tie, than they are at their inner ends. 80 They are both arranged at an equal angle to the middle rib and are spaced an equal distance apart from the same and form wedge shaped spaces between the same, the wide end of said spaces being next to the outer end 85 of the tie, or the end of the plate which carries the lip or flange B.

90 In applying the plate it is laid longitudinally upon the top of the tie with the flange B next to the outer end of the tie and the plate is hammered or pressed down to the tie, so that the ribs C C¹ C bury in the grain of the wood in approximately longitudinal position to the grain, causing the wood of the tie to enter the convergent spaces between 95 the ribs like wedges and these wedge shaped portions of the wood of the tie entering between the ribs are in such relation to the ribs that any pressure of the plate outwardly, from the tendency of the rails to spread, is 100 opposed by the wedging action of the embedded wood between the ribs while any reverse movement of the plate toward the center of the tie is opposed by a like wedging action of the wood outside of the outer ribs. 105 This makes the tie plate cling to the wood of the tie with a tightening effect as against 110

movement of the rail transversely to its length, making a very firm connection between the rail and the tie and preventing all looseness and tendency to rattle.

- 5 By making the upper surface of the tie plate inclined, getting thinner toward the inner edge, the rails R are canted inwardly a little toward the middle of the track to resist spreading action, while on curves the 10 thick side of the plate may be put on the outside of the curve for each rail, thus causing centrifugal action of the cars in turning the curve to have a tendency to force the rails up to a tighter engagement beneath the 15 strong overhanging lip B. There is also an important correlated effect between this inclined upper surface of the plate and the plurality of sets of spike holes D¹ D² D³. That is to say, when a heavier weight of rail is 20 used, the center line of the rail drops a little lower on the plate owing to the incline, so that the heads of rails of different weights are held at practically the same elevation, and this is due to the combined effect of the 25 incline and the plurality of spaced spike openings for taking different widths of rail base.

The plural sets of spike openings are arranged in staggered relation to avoid lines 30 of weakness and the extension of the ribs C C¹ C past all of the sets of holes reinforces the plate at this point and relieves it of any weakness that might otherwise exist from a multiplication of spike holes. That this may 35 be better understood, it will be seen from Fig. 2, that one of the holes D¹, D², D³, of each pair through the plate is on one side of the convergent ribs and the other hole of each pair is on the other side of the convergent 40 ribs and the ribs extend through and between the two groups to a point beyond the same, so that the bending or breaking of the plate on a line parallel with the rail through any pair of holes, as D¹ D¹, D² D², or 45 D³ D³, is prevented by the reinforcing effect of the ribs. It will be seen that as there are two holes for each width of rail and a plurality of such pairs, the plate would be weakened against the depression of the rail under

the weight of the train were the plate not reinforced past and through the groups of spike holes.

In making use of the invention, it is to be understood that the plate may be made of any size and adapted to carry any number 55 of different weights of rail and the thickness and proportion of parts may be varied without departing from the invention as set forth in the claims.

We claim—

1. A railroad tie plate having on its upper surface an overhanging lip at one side, said plate being made with an inclined upper face and decreasing thickness from said lip toward the other side and having along this 65 thinner side a plurality of pairs of spike holes, each pair being spaced a different distance from the overhanging lip to correspond to the different widths of rail bases of different weights of rails, and ribs to engage the 70 tie formed upon the lower side of the plate and extending between the spike holes of each pair and entirely past the plural pairs of spike holes, said ribs being straight and converging toward each other between the 75 spike holes of each pair and of uniform cross section with sharp lower edges adapted to bury into the wood of the tie and hold with a wedging effect.

2. A railroad tie plate having on its upper 80 surface an overhanging lip on one side and formed on its lower side with sharp ribs inclined to each other, said ribs being widest apart at the side of the plate which bears the lip and converging therefrom inwardly, and 85 said plate having a plurality of pairs of spike holes arranged at varying distances from the overhanging lip and each pair having its two holes on opposite sides of the converging 90 ends of the ribs.

In testimony whereof we affix our signatures in presence of two witnesses.
